(57) **CLAIM**

The ornamental design for a locker, as shown and described.

DESCRIPTION

FIG. 1 is a front perspective view of a locker showing our new design;

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof; and,

FIG. 8 is another front perspective view thereof, shown in a used condition with two doors in an open position.

The broken lines and the unshaded regions bounded by broken lines in FIG. 8 form no part of the claimed design.
